(57) **CLAIM**

The ornamental design for the spool organizer, as shown and described.

DESCRIPTION

FIG. 1 is a right side elevational view of the spool organizer without spools in a retracted or stored position, according to an embodiment of the present invention.

FIG. 2 is a right side elevational view of the spool organizer without spools in an extended position, according to an embodiment of the present invention.

FIG. 3 is a front elevational view of the spool organizer without spools, according to an embodiment of the present invention; and,

FIG. 4 is an isometric view of the spool organizer without spools in an extended position, according to an embodiment of the present invention.

The left side elevational view of the spool organizer without spools in a retracted or stored position is a mirror image of the right side elevational view of FIG. 1.

The left side elevational view of the spool organizer without spools in an extended position is a mirror image of the right elevational view of FIG. 2.
